Primary Examiner — Michael A Maharajh(74) *Attorney, Agent, or Firm* — Sterne, Kessler, Goldstein & Fox P.L.L.C.(57) **CLAIM**

The ornamental design for a vibrating ball, as shown and described.

DESCRIPTION

FIG. 1 is a perspective view of a vibrating ball, showing our new design;

FIG. 2 is a front elevational view thereof;

FIG. 3 is a rear elevational view thereof;

FIG. 4 is a right side elevational view thereof, the left side elevational view being a mirror image thereof;

FIG. 5 is a top plan view thereof;

FIG. 6 is a bottom plan view thereof; and,

FIG. 7 is a cross-sectional view taken along line 7--7 of FIG. 6 thereof.

The broken lines shown in the figures are for the purpose of illustrating portions of the vibrating ball that form no part of the claimed design.
